UNITED STATES PATENT OFFICE

JAMES ALTON MAY, OF NASHVILLE, NORTH CAROLINA

FLOOR OILER

Application filed October 20, 1928. Serial No. 313,823.

This invention relates to a device for applying oil and the like to floors and other surfaces, the general object of the invention being to provide a wheel supported receptacle containing the oil, valve means for controlling the flow of oil from the receptacle, brush means for spreading and rubbing the oil into the surface and means associated with the handle of the device for adjusting the valve means to regulate the flow and to close the valves.

A further object of the invention is to provide a plurality of nozzles in the bottom part of the receptacle through which the oil escapes, with a spring actuated valve for each nozzle and a supporting member for the valves to which the actuating means are connected so that the valves will be adjusted simultaneously from the actuating means, while the spring means of each valve act to compensate for wear and permits limited movement of each valve independent of the other valves.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a side view of the device.

Figure 2 is a top plan view.

Figure 3 is a section on line 3—3 of Figure 1.

Figure 4 is a section on line 4—4 of Figure 3.

Figure 5 is a section on line 5—5 of Figure 1.

Figure 6 is a view of one of the hinge members for the brushes.

In these views, the numeral 1 indicates the body of the device which is made in the form of a tank with a tapering lower part, the bottom of which is formed of a strip 2 having a longitudinal row of nozzles 3 there-

in through which the liquid in the tank will drop upon the surface over which the device is traveling. The top of the tank is flat and has an elongated opening therein which is closed by a cover 4 which is held in place by the thumb screws 5 carried by the cross strips 6 which pass across the opening. This cover is provided with a filling opening which is closed by a screw cap 7 so that oil or other liquid can be placed in the tank without removing the cover. The device is supported by the casters 8, one of which is arranged at each end of the device, these casters being suitably connected with the strip 2. A yoke-shaped member 9 has its limbs fastened to the ends of the device by the bolts 10 which also act to hold the casters in place. This yoke-shaped member is provided with a centrally arranged socket 11 for receiving the handle 12 and a brace 13 connects the socket part with an upright 14 which is fastened to a cross strip 15, the ends of which are connected with the limbs of the yoke member.

A bar 16 is arranged in the tank above the nozzles and is slidably arranged on the uprights 17 which are carried by the strip 2, springs 18 being placed on the uprights and bearing against the bar 16 and nuts 19 on the upper ends of the uprights, these springs tending to press the bar downwardly. A plurality of valves 20 have the upper ends of their stems extending into holes formed in the bar 16 and these valves are movably connected with the bar by the pins 21 which pass through the upper ends of the valve stems into the bar, the holes in the valve stems being larger than the pins so as to permit limited movement of the valves. Each valve is formed with a seat engaging part 22 for engaging a seat 23 formed at the upper end of each nozzle and with a tapered part 24 for engaging the tapered hole in each nozzle. A spring 25 encircles each valve stem and presses against the bar and the valve for holding the valve upon its seat when the bar is in lowered position. A rod or stem 26 has its lower end connected with the middle part of the bar and passes through a hole in the cover 4, with its upper end grooved to receive the forked end of a lever 27 which is pivoted to the upright 14. The other end of the lever is piv-

oted to a rod 28 which passes through the handle and has its upper end threaded to engage a threaded hole in a hand grip 29 which is rotatably connected with the upper end of the handle by a sleeve 30 so that by turning this hand grip, the rod 28 will be moved longitudinally and thus tilt the lever 27 on its pivot to raise or lower the bar 16 through means of the rod or stem 26, thus permitting adjustment of the valves through means of the hand grip. As will be understood, this adjustment can be such as to regulate the flow of liquid through the nozzles or by moving the bar downwardly to a certain extent, the valves will be made to entirely close the nozzles and thus shut off the flow of oil from the device.

A pair of hinge members 31 is held to the bottom part of the strip 2 by the bolts 10 and 20 brush or mop carrying members 32 are hingedly supported by these members 31. Each member 31 is provided with a downwardly extending tongue 33 which act as stops for limiting the downward movement 25 of the members 32. Each member is provided with a casing-like part 34 having perforations in its lower part for receiving the mop material or if desired, this material can be substituted by bristles. As will be seen, these 30 members are arranged at an angle to the surface being oiled and are located at each side of the row of nozzles so that they will act to distribute the oil dropping from the nozzles as the device is moved in either direction and 35 they will also act to rub the oil into the surface.

From the foregoing it will be seen that it is simply necessary to move the device over the floor or other surface to be oiled or treated, 40 the flow of oil being controlled by the hand grip at the end of the handle so that just the desired amount of oil can be supplied to the floor. As the device moves along, the mops will act to distribute the oil and to rub the 45 same into the surface. After sufficient oil has been applied to the surface, the flow of oil can be cut off and then the device used to rub the oil into the surface and to polish the surface. As the mop members are detachable, 50 new ones can be substituted whenever desired. By hinging the mop carrying members to the body, it will be seen that these members can accommodate themselves to irregularities in the floor, though their weight will hold the 55 mop material on the floor.

It is thought from the foregoing description that the advantages and novel features of the invention will be readily apparent.

It is to be understood that changes may be 60 made in the construction and in the combination and arrangement of the several parts, provided that such changes fall within the scope of the appended claims.

What I claim is:—

65 1. A device of the class described comprising

ing a body made in the form of a tank, wheels for supporting the body, nozzles depending from the body, valve means for controlling the flow of liquid through the nozzles, a handle connected with the body, means associated with the handle and with the valve means for moving the valve means to closed position or for adjusting the valve means to regulate the amount of liquid passing through the nozzles and a pair of mop carrying members hingedly 70 connected with the lower part of the body, one on each side of the row of nozzles and stops connected with the bottom of the device for limiting the downward movement of the hinged mop carrying members. 75

2. A device of the class described comprising a body made in the form of a tank, wheels for supporting the body, a row of nozzles depending from the body, a handle connected with the body, a rod passing through the handle, means at the outer end of the handle for moving the rod longitudinally, a lever pivoted to a part of the body and connected with the lower end of the rod, a bar in the tank, a stem connected therewith and passing 90 through the top part of the tank and connected with the lever and a row of valves carried by the bar and extending into the nozzles. 95

3. A device of the class described comprising a body made in the form of a tank, wheels for supporting the body, a row of nozzles depending from the body, a handle connected with the body, a rod passing through the handle, means at the outer end of the handle for moving the rod longitudinally, a lever pivoted to a part of the body and connected with the lower end of the rod, a bar in the tank, a stem connected therewith and passing through the top part of the tank and connected with the lever, a row of valves carried by the bar and extending into the nozzles, each valve being movably connected with the bar and a spring on each valve and arranged between the valve and the bar. 100

In testimony whereof I affix my signature. 110
